CLAIM

The ornamental design for a vehicle wheel, as shown and described.

DESCRIPTION

FIG. 1 is an isometric view of a top, front, and left side of an ornamental design for a vehicle wheel; and, FIG. 2 is a front elevational view of the vehicle wheel of FIG. 1.

The dash-dash-dash lines illustrate portions of the vehicle wheel that form no part of the claimed design. The dash-dot-dash lines are included for the purpose of illustrating boundary lines and form no part of the claimed design.

1 Claim, 2 Drawing Sheets
